UNITED STATES PATENT OFFICE

ARTHUR A. JOHNSON, OF NEW YORK, N. Y., ASSIGNOR TO UNDERWOOD COMPUTING
MACHINE COMPANY, OF NEW YORK, N. Y., A CORPORATION OF NEW YORK.

COMBINED TYPE-WRITING AND COMPUTING MACHINE.

1,304,570.

Specification of Letters Patent. Patented May 27, 1919.

Application filed August 2, 1916. Serial No. 112,645.

To all whom it may concern:

Be it known that I, ARTHUR A. JOHNSON, a citizen of the United States, residing in borough of the Bronx, in the county of the Bronx, city and State of New York, have invented certain new and useful Improvements in Combined Type-Writing and Computing Machines, of which the following is a specification.

- 10 This invention has reference to combined typewriting and computing machines, and in particular to machines provided with means for automatically spacing to point off the digits of numbers being written.
- 15 It has been proposed to provide mechanism whereby the typewriter carriage, as it travels through a computing zone, is automatically spaced at various times to point off the digits of the number written, so as 20 to render the number easily readable, for instance between the millions digit and the hundred-thousands digit, the thousands digit and the hundreds digit, etc.

Machines of this character are usually 25 provided with decimal tabulating mechanism for assisting the operator in locating the typewriter carriage at the proper position for commencing typewriting; for example, should the operator desire to write 30 "1,000" the thousands tabulating key is depressed, whereupon the carriage is released by said key and caused to travel under the tension of the driving spring until stopped by a column stop on the carriage striking 35 a coöperating stop moved into its path by the depression of the tabulating key, the column stop being settable on the carriage. The column stops, in order that they may be easily set by the operator, are usually of the 40 key-set type, in which one stop is provided for each letter space of the machine, the stops being normally out of operative position and settable individually by means of a key at the key-board of the machine, such 45 as shown in the patent to Doane No. 1,157,683. These stops are not only used to position the carriage when writing numbers, but also to position the carriage in carrying out such other kinds of work as require 50 the carriage to be started at a definite predetermined position.

In typewriting and computing machines

having mechanism which enables the carriage to be automatically spaced for punctuation, it is advantageous to operate the 55 said mechanism by or from a tabulating stop, for the reason that the tabulating stop is almost invariably used to locate the carriage in the proper position in the computing zone and therefore is a usual fixed attachment to the machine. Heretofore however, it has been seemingly impossible to utilize the key-set tabulator stops for this purpose because of this very universality of the stops, for it will be seen that, since all 60 of the stops must be identical in order that any one may be used in the ordinary manner and for the same purposes as the others, it would necessarily result that all of the stops which are set would operate the automatic spacing device, although the operation of said device is obviously not desired except when the carriage is in the computing zone.

An object of the invention is to overcome 75 the above noted obstacle to the use of the key-set tabulator stops, and provide means whereby the set stops which control the positioning of the carriage at a computing zone, are also effective to control the double-spacing mechanism for punctuating a number, whereas the other set tabulating stops are ineffective to cause such double-spacing.

This invention is herein disclosed as an improvement on the inventions disclosed in 85 the application of Frederick A. Hart, Serial No. 79,969, filed February 23, 1916, (now Patent No. 1,282,823, dated October 29, 1918,) and the application of William L. Gumprecht, Serial No. 89,015, filed April 90 5, 1916.

In said applications, the mechanism includes an escapement wheel which coöperates with a fixed and loose dog both supported by a pivoted dog rocker, the latter controlled by character keys, to effect letter-feed movements of the typewriter carriage. Said applications also include mechanism to effect double letter space movements of the typewriter carriage at predetermined positions where it is desired to space between the figures by automatically shifting a stop member, which controls the throw of the loose dog, the stop member being shifted by 95 100

means of a tappeted bail, which is engaged by a projection on an adjustable element traveling with the carriage.

In accordance with the present invention, 5 the tappeted bail may be controlled and operated by the set tabulating stops which control the positioning of the carriage at the computing zone. In order that the other set stops may not actuate the tappeted bail, the latter is normally held out of 10 the path of said stops, but may be automatically brought into operative position as the carriage reaches a computing zone. Where the machine comprises one or more 15 totalizers, the means for setting the tappeted bail for operation may be carried for adjustment with the totalizers, and, more specifically, may comprise a cam carried by each totalizer and operable through suitable 20 connections to swing the bail to operative position as the totalizer comes into the computing zone, and retain it in operative position only until the totalizer passes beyond the computing zone.

25 In combined typewriting and computing machines the numeral keys are usually provided with, or operate means controlling the action of the computing mechanism between the numeral keys and the totalizer, 30 and it has been found advantageous to provide means whereby the numeral keys may be disconnected from the computing mechanism so as not to cause undue wear of said mechanism when it is not desired to compute. A feature of the present invention is 35 the provision of improved means whereby the numeral keys of the typewriting machine may be normally disconnected from the computing mechanism, but which when the typewriter carriage approaches the computing zone causes the keys and the computing mechanism to be automatically connected.

This may be done, for instance, in the 40 manner illustrated in the accompanying drawings, in which a clutch is provided to normally break the train of connections between the keys and the totalizer; and in which is provided means, which, when the typewriter carriage approaches the computing zone, causes the clutch to connect the keys and the computing mechanism.

Another feature is the provision of silencing means for the computing mechanism, 45 whereby, the means for automatically connecting the numeral keys and computing mechanism, may be made ineffective, even if already in the computing zone. Said silencing means may comprise a non-add key, 50 and a platen shift key, and means operable by either of said keys to take the computing mechanism out of the control of the numeral keys.

The invention provides means whereby 55 either the non-add key or the platen-shifting

key is operative to disable the connections between the numeral keys and the computing mechanism, and also to disable the double-spacing means, so that when either the non-add key or the shift key is actuated, both the computing mechanism and the double-spacing mechanism are silenced.

While the invention is illustrated as applied to a machine having tabulator stops of the key-set type, it will have many similar advantages wherever it is found desirable to have all of the tabulating stops identical, so that the operator cannot make an error by placing the wrong kind of a stop at any position on the machine.

80 Other features and advantages will hereinafter appear.

In the accompanying drawings,

Figure 1 is a part sectional side elevation of a combined typewriting and computing machine, constructed in accordance with the principles of the present invention.

Fig. 2 is a skeleton perspective view, showing the numeral keys and the computing mechanism, comprising an actuating element 85 which is operated by the numeral keys, the "9" key being depressed to effect a combined typewriting and computing operation.

Fig. 3 is a fragmentary front perspective view, showing particularly an escapement mechanism, a tappeted bail controlling the stop device for the escapement dog, column stops for actuating said tappeted bail, and means controlled from the totalizer for rendering the double-space effecting means and 90 the computing mechanism effective.

Fig. 4 is a front view of the escapement mechanism with the parts in their normal position of rest, in which position the escapement wheel is held by the loose dog.

Fig. 5 is a similar view, but with the upper part of the dog rocker moved rearwardly and the escapement wheel held by the fixed dog, the loose dog being positioned by the variable stop device as in ordinary 100 letter-feeding.

Fig. 6 is a view similar to Fig. 5, except that the stop device is positioned to permit a double-space throw of the loose dog.

Fig. 7 is a view similar to Fig. 1 with 115 some of the parts omitted, and shows the tappeted bail shifted, by the totalizer, to an effective position where it can be engaged by the column stops for the purpose of shifting the variable stop device to effect double-space movements of the carriage.

Fig. 8 is a schematic view of my invention as embodied in the present disclosure.

The typewriting mechanism which, in most respects, is the same as that found in 125 the usual commercial Underwood machine, comprises a carriage 11 mounted to travel on front and rear guide rails 12 and 13, the carriage being propelled by a spring motor 14 connected through a band 15 to the car- 130

riage. A roller platen 16 has an axle 17 journaled in the platen frame 18 shiftable up and down on the carriage to bring the platen to upper and lower-case positions. A

5 shift-key 19 fulcrumed at 20 has an arm 21 extending upwardly behind the platen shift frame 22 fulcrumed at 23 and comprising a shift rail 24 on which runs a roller 25 on the platen frame. When the shift-key is de-
10 pressed, the shift-frame 22 is operated to shift the platen to upper-case position.

Type-bars 26 carrying upper and lower case types 27, 28, are mounted on a curved fulcrum rod 29 to swing upwardly and rear-
15 wardly; to cause the types to strike against the front face of the platen. Alphabet keys 30 and numeral keys 31 are fulcrumed at 20 and are connected through bell-cranks 32 to their respective type-bars for actuating the
20 latter.

The escapement mechanism which controls the letter-feed movements of the carriage, comprises an escapement wheel 33 having a one-way driving connection through dogs 34 with an escapement pinion 35, which runs in mesh with a carriage rack 36, the latter carried by arms 37 pivotally mounted on the carriage to permit the rack 36 to be swung off the escapement pinion.
25 The escapement wheel 33 has a step-by-step movement controlled by a fixed dog 38 on a dog-rocker 39 and a loose dog 40 pivoted at 41 to the dog-rocker. The latter is actuated at each type-stroke by means of a universal bar 42 in the path of shoulders 43 on the type-bars, so that when a type-bar is operated and rises to printing position, the universal bar 42 swings the upper end of the dog-rocker rearwardly. The universal bar
30 40 is returned by a spring 44.

Figs. 3 and 4 show the parts in their normal position of rest, wherein the escapement wheel is held by the loose dog 40 against which bears one of the teeth 45 of the escapement wheel. When a type-bar is operated and the upper end of the dog-rocker 39 is swung rearwardly, as above noted, the fixed dog 38 is brought into the path of said tooth and holds the escapement wheel while the loose dog is moved rearwardly out of engagement with said tooth and thereby released to its spring 46 (Fig. 4), which swings the dog to the left until arrested by a stop 47 (Fig. 5) in the path of a pin 48 on the
55 dog.

As the actuated type-bar returns and permits the universal bar to be returned by its spring 44, the spring 46 returns the dog-rocker 39, thereby swinging the pivoted dog
60 40 forward in front of the next tooth of the escapement wheel, and also swings the fixed dog 38 forward out of the path of the wheel, permitting the latter, under the influence of the carriage spring, to be rotated the dis-
65 tance of one tooth, that is, a normal letter-

space distance. The pivoted dog, during this movement of the wheel, is swung to the right until arrested by a stop on the dog-rocker.

Tabulator mechanism may be provided comprising tabulator keys 49 connected to levers 50 pivoted at 51 to operate decimal-tabulator stops 52, said stops being in the form of vertical bars or plungers mounted for vertical movement in a tabulator frame 75 53. Column stops 54 are mounted at letter-space intervals on a rack 55 on the carriage. The stops 54, as shown, are mounted for a limited vertical movement in the rack bar 55, so that any desired stop may be set or moved downward in the rack to operative position, namely, to a position to be intercepted by any denomination stop 52 which has been projected by depressing its key 49. The stops 54 may be selectively set as desired by any suitable form of key-actuated selective stop-setting mechanism, such as shown, for example, in the patent to Doane No. 1,157,683 above referred to.

When any one of the plunger stops 52 is actuated, it operates through a pivoted universal bar 56, connected through a link 57 to a lever 58 carrying a roller 59, to lift the rack bar 36. The carriage is thus released from the control of the escapement mechanism and permitted to run forward until arrested by a set stop 54 engaging the projected stop 52, thereby positioning the carriage at the column and the denominational position in the column, determined by the effective stops 54 and 52, respectively.

The computing mechanism may comprise one or more totalizers 60 each connected to travel with the carriage by means of a latch 61 engaging a rack bar 62 on the carriage, whereby the totalizer may be adjusted through letter-space intervals to any desired position lengthwise of the carriage. Each totalizer is provided with guide rollers 63 and 64 to run on a rail 65 on the machine frame. The totalizer comprises dial wheels 66 and computing wheels 67 actuated by the mechanism mounted on the machine frame, said mechanism comprising a master wheel 68 which, during the writing of the several digits of a number, is brought into operative relation with the computing wheels 67 successively and operates said wheels to run up on the dial wheels the number being written.

The operating means between the numeral keys 31 and the computing wheels comprises differentiators 69 on the numeral-key-levers, each differentiator being in the form of a plate with a cam slot 70. An actuating element 71 comprises a rod 71^a which extends across the machine in position to be actuated by any one of said differentiators, said rod being carried by swinging arms 72 journaled on a shaft 73. When any numeral key is depressed, the cam slot 70 of the corre- 130

sponding differentiator is moved downward over the rod 71^a, so that the latter is cammed forward (Fig. 2). The upper ends of the slots are in stepped relation, the slots being so formed that the extent of movement imparted to the actuating element 71 will correspond with the value of the digit represented by the actuated key, so that the computing mechanism will be operated a corresponding extent.

10 The connections between the differentiators and the computing wheels may comprise a floating lever 74 provided with a notch 75 to receive a pin 76 on an arm 72, at the proper time. Said lever 74 is pivoted at 78 to a lever 79 fulcrumed at 73. Said lever 74 when in its effective position is held against the pin 76 by a spring 80, so that the forward movement of the actuating element 71 when 15 a key is depressed, operates through the pin 76 and lever 74 to swing lever 79 about its fulcrum, and thereby move downwardly a link 81 connected to a rock arm 82 on a shaft 83.

20 25 A second arm 84 on the shaft 83 is connected through a link 85 to a rack 86, which drives the pinion 87, fixed to a shaft 88. A gear wheel 89 which rotates with the pinion 87, is shiftable by means of an add or subtract key into direct driving relation either to a pinion 90 or a pinion 91, the latter being connected to drive the master wheel 68. The pinion 90 may be at all times in driving 30 relation with the pinion 91. In adding, the

35 gear wheel 89 operates through the pinions 90 and 91 to drive the master wheel in one direction, and in subtracting the gear wheel 89 drives the master wheel directly through the pinion 91 in the opposite direction. The 40 operation of the computing mechanism thus far described may be substantially like that disclosed in the application of Henry L. Pitman, No. 81,574 filed Mar. 2, 1916.

45 Before a computing operation, the totalizer may be adjusted to a position corresponding to that of a set tabulator stop 54. The numeral keys may be operated in the usual manner to print any desired number. As each numeral key is depressed, it operates 50 through the connections above described to rotate the master wheel 68 through a distance corresponding to the digit of the particular key operated. The master wheel drives the particular computing wheel 67 55 and dial wheel 66 which are at the time being, in register therewith, to run up on the totalizer the corresponding number. Such operation takes place during the depression of the numeral key. As said key is returned, 60 the escapement mechanism permits the carriage to advance a letter-space distance, thereby bringing the master wheel into register with the next succeeding computing wheel.

65 In order to automatically point off or

space at the decimal positions and between the digits in the hundreds and thousands positions, etc., mechanism is provided for automatically effecting a double-space letter-feed movement of the carriage when such 70 positions are reached. For this purpose, the throw of the loose dog 40 of the escapement is variably controlled by a shiftable stop device 92 in the form of a lever pivoted on a stud 93 on the escapement frame, the lever 75 being held against endwise displacement on the stud by nuts 94. Said stop device comprises the stop 47 heretofore referred to, which normally limits the throw of the dog 40, and a second stop 95 which may be alternatively brought into position to control 80 said dog for a double-space movement. The stop device 92 is actuated or set for causing a double-space movement, by means of the column stop or engaging member 54 on the carriage, which engages tappets 96 on a bail 96^a pivoted at 97 to a swinging frame 98 mounted by pivots 99 on the tabulator frame 53. The bail 96^a comprises a forwardly-extending arm 100 connected through a link 101 to a rearwardly extending arm 102 of the stop device 92. A spring 103 is connected to the arm 100 to bear downwardly thereon and thereby normally hold the stop device 92 in the Fig. 4 position, in which the 95 stop 47 is operative, the movement of the stop device by said spring being limited by a projection 104 thereon striking the escapement frame 105.

100 It will thus be seen that the bail 96^a, including the arm 100, constitutes a floating bell-crank lever, its floating fulcrum being the pivot points 97 on the frame 98, which frame is pivoted to swing from the tabulator frame 53 at the points 99. Said frame 98 105 normally holds the tappeted bail 96^a in position out of the path of the column-stops 54, even though said stops are in set positions. This position of the parts is shown in Fig. 1, wherein the arm 100 is shown in substantially horizontal position, while the tappets 96 are out of the path of any tabulator stop. This position of the tappeted bail results 110 from the joint action of the frame 98, (which is held in the position of Fig. 1 by spring 115 123 to be described later) and the projection 104 on the stop device 92 acting to prevent spring 103 from moving the tappeted bail to such position that the tappets would be in the path of any set stop 54.

120 As described in the Pitman application herein before mentioned, each totalizer is provided with a cam 106, the same length as the totalizer, each cam in said Pitman application serving as part of the carry-over mechanism. As the totalizer traverses a computing zone, the cam operates levers 107, pivoted on a rod 108, to move them *seriatim* away from levers 109, which act as detents for carry-over wheels 110. The cam 106 in 125 130

the present invention is operative through connections which will now be described, to render the tappeted bail 96^a effective. As the totalizer enters the computing zone, the 5 cam 106 engages a lever 111 of the first order pivoted on the rod 108 and depresses the forward end of the lever. This causes the rear end of the lever to pull upwardly a link 112 connected to a lever 113 and swing the latter.

10 The lever 113 has an arm extending rearwardly from its fulcrum and provided with an offset 118 which engages beneath an arm 117 of a bell-crank 115, also fulcrumed on the rod 114. The bell crank 115, is held 15 against the offset 118 by a coil spring 116, (Fig. 3), which has one end overlying the lever 113, and the other overlying the arm 117, being coiled around the rod 114, so that 20 when the lever 113 is operated by the cam 106, the bell crank is swung downwardly, around its fulcrum rod 114. The arm 117 is connected by a link 119 to an arm 120 extending forwardly from the frame 98. Thus 25 the upper end of the frame 98 is moved forwardly through the train of connections above described, and carries the tappeted bail 96^a with it to bring the tappets 96 into the path of the column stops 54.

30 The lever 113 and bell crank 115 are located near the middle of the machine and are held in position on the rod 114 by collars 121 and 122 secured to the rod 114. The spring 116 which forms a flexible connection between 35 the lever 113 and bell crank 115, so that they always tend to move together, also holds said lever and bell crank laterally against the collars 121 and 122 respectively.

To explain the operation of the double-spacing mechanism, let it be assumed that 40 the totalizer is in the computing zone at the ten-thousands position, it being understood that the tappeted bail at this time is in its effective position (Fig. 7). If now a numeral key is operated to print a digit in such position, the carriage will, upon the return of the key, advance a single letter-space distance, as usual; the escapement wheel, during such advance of the carriage, operating to swing the loose dog from the Fig. 5 position to the Fig. 4 position. During this movement of the carriage, however, a tappet 45 96 strikes the column stop 54, and the bail 96^a is swung rearwardly about its pivot 97 and through the link 101 swings the stop device 92 from the Fig. 5 position to the Fig. 6 position. The carriage is now at the 50 thousands position, so that the next numeral key struck prints in the thousands place. During this printing operation, the upper end of the dog-rocker 39 is swung rearwardly, as usual, to release the loose dog, which is now permitted to swing to the Fig. 6 position, owing to the position of the stop 55 device 92, so that when the dog-rocker is

returned, the loose dog permits the escapement wheel to advance a distance of two teeth, thereby effecting a double letter-space movement of the carriage. Thus the next operated numeral key will print in the hundreds place, a double letter-space in advance of the preceding digit. The double space movement of the carriage moves the column stop 54 off the tappet 96, so that the stop device 92 is reset by the spring 103 to the 70 Fig. 4 position, whereby the carriage will only be permitted a single letter-space movement at the next printing operation.

As above stated, the computing mechanism is normally disconnected or out of the control of the numeral keys. The parts are held in their disconnected position by a spring 123 (Fig. 1) which pulls on an arm 124 on a rock shaft 125 and causes a finger 126 on a second arm 127 to engage with the lever 74 to hold the latter out of engagement with the pin 76 on the indexing element 71. If a numeral key is now actuated, the actuating element will be moved idly by the differentiator 69 associated with the particular key operated. The spring 123 is located near the right hand side of the machine with its end fastened by a pin 123^a on the machine frame. Incidentally the spring 123, through the link 129, bell-crank 95 arm 128, spring 116 and lever 113, normally holds the front end of the lever 111 in the path of the cam 106, and also tends to move the bail 96^a to ineffective position.

The computing mechanism is rendered 100 effective by connecting the lever 74 with the actuating element 71, every time a totalizer passes through the computing zone, at which time the cam 106 on the totalizer engages with the lever 111 to cause an upward pull 105 on link 112 and swing lever 113 and the bell crank 115 as hereinbefore described. The bell crank 115 has a downwardly projecting arm 128 which pushes on a link 129 connected to an arm 130 secured to the shaft 125 110 to rock the latter. When the shaft 125 is rocked, the arm 127 thereon carries the finger 126 out of the path of the lever 79 and permits the lever 74 to be swung into engagement with the pin 76 on the actuating 115 element 71. The spring 80 is effective to connect the lever 74 with the actuating element 71 and hold it in its connected position until the totalizer 60 passes out of the computing zone, when the parts are returned 120 to their normal position (Fig. 1), by the spring 123. While returning to normal position, the finger 126 engages with the lever 74 to swing it against the tension of the spring 80 and disconnect it from the actuating 125 element 71.

The computing mechanism is silenced by a "non-add" key 131 connected through a link 132 to the arm 124 on the rock shaft 125. When the key 131 is moved to the 130

dotted line position indicated in Fig. 7, the connecting pin 131^a between said link and key is brought to a dead-center position in line with the pivot of the key 131 and the rear pivot of the link, as indicated by the broken line X—X, Fig. 7. The rock shaft 125 is thus locked in position to hold the lever 74 down and thereby prevent operation of the computing mechanism. Thus it will be seen that, if a totalizer now passes through the computing zone, as shown in Fig. 7, the cam 106 will cause a movement of the lever 113, but said movement will be ineffective to move the bell crank 115, owing to the connections 129, 130 between the bell crank and the rock shaft 125 which is at this time locked against movement as above pointed out. It will be further seen that as the bell crank 115 is held in its ineffective position (shown in dotted lines, Fig. 7), the tappeted bail 96 at this time, is also prevented from being moved to its effective position.

To prevent computing when the platen is shifted to its upper case position, which is desirable when the lower case types on the numeral type bars are numerals and the upper case types are other characters, I have provided means controlled from the shift key 19, for locking the rock shaft 125 in its normal position, when the shift key is depressed. For this purpose a link 133 is pivoted to the platen shift frame 22 and extends forwardly therefrom and has a slot-and-pin connection 134 at its forward end with an arm 135 on the rock shaft 125. When the shift key is depressed, the link 133 is moved forwardly and locks the arm 135 and rock shaft 125 against movement from the Fig. 1 position. Since the rock shaft 125 is thus prevented from moving while the platen is shifted to upper case position, it will also be understood that the bail 96 is prevented from being moved to its effective position. If a totalizer now passes through the computing zone, while the shift key is depressed it will move only the lever 111, link 112 and the lever 113, the bell crank 115 being locked against movement, indirectly through link 133.

Variations may be resorted to within the scope of the invention, and portions of the improvements may be used without others.

Having thus described my invention, I claim:

1. In a combined typewriting and computing machine the combination of a carriage, a tabulator stop on said carriage, means for propelling said carriage, a computing mechanism including an element traveling with said carriage to control denominational selection of the computing mechanism, and a means rendered effective, by said traveling element, to engage with said tabulator stop.

2. In a combined typewriting and computing machine the combination of a carriage, a tabulator stop on said carriage, means for propelling said carriage, a totalizer traveling with said carriage, and means normally ineffective and rendered effective by said traveling totalizer to engage with said tabulator stop to perform a desired function.

3. In a combined typewriting and computing machine, the combination with computing mechanism, of a carriage, a stop-bar carried thereby, column stops in effective positions on said stop-bar, means for propelling said carriage, a variable feed escapement for said carriage, means for permitting double-space movements of the carriage, and means for causing said double-space-permitting means to be actuated by any of said column stops in a computing zone.

4. In a combined typewriting and computing machine, the combination with computing mechanism, of a carriage, means for propelling said carriage, a variable feed escapement for said carriage, a tabulator stop, means controlled from said tabulator stop for permitting double space movements of the carriage at predetermined positions in its travel, said double-space-permitting means being normally ineffective, and means acting in a computing zone for rendering said double-space-permitting means effective to be engaged by said tabulator stop.

5. In a combined typewriting and computing machine, the combination with computing mechanism, of a carriage, means for propelling said carriage, a variable feed escapement for said carriage, an adjustable element traveling with said carriage and determining a computing zone, means controlled from said adjustable element for permitting double space movements of the carriage at predetermined positions in its travel in said zone, said double space-permitting means being normally ineffective, and means for rendering said double space-permitting means effective to be engaged by said adjustable element.

6. In a combined typewriting and computing machine, the combination with computing mechanism, of a carriage, means for propelling said carriage, a variable feed escapement for said carriage, two elements traveling with said carriage, one of said elements determining denominational selection of said computing mechanism, and the other of said elements determining different positions for said carriage, and means for permitting double-space movements of the carriage at predetermined positions in its travel, said double-space-permitting means being rendered effective by said denominational determining element, after

which it is engaged by the other of said two elements to effect a double-space movement of the carriage.

7. In a combined typewriting and computing machine, the combination with computing mechanism and denominational selecting means therefor, of a carriage, means for propelling said carriage, a variable feed escapement for said carriage, a cam engageable by said denominational selecting means, and means for permitting double-space movements of the carriage at predetermined positions in its travel, said double-space-permitting means being normally ineffective and rendered effective by said cam. 70

8. In a combined typewriting and computing machine, the combination of a carriage, means for propelling said carriage, a variable feed escapement for said carriage, two members namely, a totalizer and a tabulator stop traveling with said carriage, and means for permitting double-space movements of the carriage at predetermined positions in its travel, said double-space-permitting means being normally ineffective and rendered effective by one of said members, after which it is engaged by the other of said two members to effect a double-space movement of the carriage. 85

9. In a combined typewriting and computing machine, the combination with computing mechanism of a carriage, means for propelling said carriage, a variable feed escapement for said carriage, two elements traveling with said carriage, one of said elements determining denominational selection of said computing mechanism, and the other of said elements determining different positions for said carriage, means comprising a pivoted member for permitting double-space movements of the carriage at predetermined positions in its travel, and a pivoted frame, said denominational determining element being effective to move said pivoted frame to bring said pivoted element carried thereby to an effective position where it can be engaged by the other of said two traveling elements. 90

10. In a combined typewriting and computing machine, the combination of a carriage, means for propelling said carriage, a variable feed escapement for said carriage, a totalizer and a tabulator stop traveling with said carriage, means comprising a tappeted bail for permitting double space movements of the carriage at predetermined positions in its travel, said tappeted bail being pivoted on a swinging frame, and means engaging with the totalizer to move said pivoted frame and render said tappeted bail effective so that it can be engaged by the tabulator stop to effect a double-space movement of the carriage. 105

11. In a combined typewriting and computing machine, the combination of a car- 110

riage, means for propelling said carriage, a variable feed escapement for said carriage, a tabulator stop, means for permitting double-space movements of said carriage at predetermined positions in its travel, said double-space-permitting means being normally ineffective, computing mechanism, and means for rendering said double-space-permitting means effective when the carriage reaches a computing zone, so that said double-space-permitting means can be engaged by said tabulator stop. 115

12. In a combined typewriting and computing machine, the combination of a carriage, means for propelling said carriage, a variable feed escapement for said carriage, means for permitting double-space movements of said carriage, a series of column stops, said double-space-permitting means being normally out of the path of said column stops, a plurality of totalizers arranged to travel with said carriage, and means engaged by said totalizers for rendering said double-space-permitting means effective, to be engaged by those column stops in columnar positions on the carriage where it is desirable to effect double-space movements of the carriage. 120

13. In a combined typewriting and computing machine, the combination with computing mechanism, of a carriage, means for propelling said carriage, a variable feed escapement for said carriage, means for permitting double-space movements of said carriage, a series of column stops, said double-space-permitting means being normally out of the path of said column stops, means for determining a plurality of computing zones during the traverse of said carriage, and means controlled by said zone-determining means for rendering said double-space-permitting means effective, to be engaged by those column stops in columnar positions on the carriage where it is desirable to effect double-space movements of the carriage. 125

14. In a combined typewriting and computing machine, the combination of a carriage, means for propelling said carriage, a variable feed escapement for said carriage, a plurality of totalizers arranged to travel with said carriage, means for effecting double-space movements of said carriage, a series of column stops, and means engaged by said totalizers for rendering said double-space-permitting means effective to be engaged by said column stops, one at a time, when the carriage reaches the corresponding columnar positions. 130

15. In a combined typewriting and computing machine, the combination with computing mechanism, of a carriage, means for propelling said carriage, a variable feed escapement for said carriage, means for determining a plurality of computing zones 135

- 2 during the traverse of said carriage, means for effecting double-space movements of said carriage, a series of column stops, and means engaged by said zone determining 5 means for rendering said double-space-permitting means effective to be engaged by said column stops, one at a time, when the carriage reaches the corresponding columnar positions.
- 10 16. In a combined typewriting and computing machine, the combination with computing mechanism, of a carriage, means for propelling said carriage, a variable feed escapement for said carriage, a series of column stops for positioning the carriage at different columnar positions, means for permitting double-space movements, in columnar positions of said carriage, and a computing element at each columnar position 15 in which the double-space movements of the carriage are to be effected, for rendering said double-space-permitting means effective.
17. In a combined typewriting and computing machine, the combination of a carriage, a variable feed escapement for said carriage, a totalizer, means controlled from said totalizer for effecting double space movements at predetermined positions in 20 the travel of said carriage, said means comprising a lever of the first order, a link, a yielding element, a second link, a pivoted frame, and a tappeted bail carried by said pivoted frame.
- 30 18. In a combined typewriting and computing machine, the combination of a carriage comprising a platen, printing mechanism comprising numeral keys, computing mechanism including a master wheel, a totalizer, a variable escapement for said carriage, an actuating element, said actuating element being normally disconnected from the master wheel, means controlled from said totalizer for connecting said actuating 35 element with said master wheel and simultaneously made effective to vary the escapement, and a device manually operable to make said means ineffective.
19. In a combined typewriting and computing machine, the combination of a carriage comprising a platen, means for propelling said carriage, a variable feed escapement for said carriage, a tabulator stop, means controlled from said tabulator stop 40 for permitting double-space movements of the carriage at predetermined positions in its travel, computing mechanism normally ineffective, means for automatically rendering said computing mechanism and said double-space permitting means effective, and a key for preventing said computing mechanism and said double-space permitting means from being rendered effective.
- 45 50 55 60 65 70 75 80 85 90 95 100 105 110 115 120 125 130
20. In a combined typewriting and computing machine, the combination of a car-

riage comprising a platen, means for propelling said carriage, a variable feed escapement for said carriage, a tabulator stop, means controlled from said tabulator stop for permitting double-space movements of the carriage at predetermined positions in its travel, printing mechanism, case-shifting mechanism comprising a key, said double-space permitting means being normally ineffective, means for automatically rendering said double-space permitting means effective when the carriage reaches a computing zone, and means for preventing said double-space permitting means being rendered effective when the carriage reaches an adding zone while the case shifting key is in its actuated position.

21. In a combined typewriting and computing machine, the combination with computing mechanism, of a carriage, means for propelling said carriage, a variable feed escapement for said carriage, two elements traveling with said carriage, one of said elements determining denominational selection of said computing mechanism, and the other of said elements determining different positions for said carriage, means comprising a pivoted member for permitting double-space movements of said carriage at predetermined positions in its travel, a pivoted frame, said denominational determining element being effective to move said pivoted frame to bring said pivoted element to an effective position where it can be engaged by the other of said two traveling elements, and means for preventing said pivoted element from being moved to an effective position.

22. In a combined typewriting and computing machine, the combination of a carriage, means for propelling said carriage, a variable feed escapement for said carriage, a tabulator stop, means for permitting double-space movements of said carriage at predetermined positions in its travel, said double-space-permitting means being normally ineffective, computing mechanism, means for rendering said double-space-permitting means effective when the carriage reaches a computing zone so that said double-space-permitting means can be engaged by said tabulator stop, and means for preventing said double-space-permitting means from being rendered effective when the carriage reaches a computing zone.

23. In a combined typewriting and computing machine, the combination of a carriage comprising a platen, means for propelling said carriage, a variable feed escapement for said carriage, means for permitting a double-space movement at predetermined positions in the travel of said carriage, an element on said carriage engaging with said double-space-permitting means to effect the double-space movement of said carriage, printing mechanism comprising numeral

keys, computing mechanism, an actuating element operable by said numeral keys, means for connecting said computing mechanism with said actuating element, said 5 double-space-permitting means being normally ineffective, and means for rendering said double-space-permitting means effective.

24. The combination with a carriage having a step-by-step letter-feeding mechanism, of a totalizer thereon, means for causing the carriage to feed through more than one letter-space at a single step movement, tabulator mechanism comprising a stop on the 10 carriage, and means operated by the totalizer for causing the tabulator stop to operate the first mentioned means.

25. The combination with keys, of a valuating mechanism, actuating mechanism, connections between the valuating mechanism and the actuating mechanism normally inoperative, a carriage, tabulating mechanism for said carriage comprising a stop, mechanism for controlling the movement of the 15 carriage adapted to be operated by said stop but normally inoperative, a totalizer on the carriage, and means controlled by the totalizer as it reaches a point in its travel with the carriage for making operative the connections between the valuating mechanism and the actuating mechanism, and also causing the mechanism for controlling the movement of the carriage to become operative.

26. In a typewriting and computing machine, the combination with a traveling carriage, of tabulator stops, one for each letter-space position of the carriage, said stops normally inoperative, and settable to operative position, a totalizer adjustable along 20 the carriage, and means controlled by the totalizer and brought into activity as the totalizer enters the adding zone and dependent upon the tabulator stop for automatically skipping the carriage through a punctuation space while a number is being written.

27. In a combined typewriting and computing machine, the combination with a paper carriage, of letter-feed mechanism comprising means for effecting double-space 25 letter-feed movements of the carriage, tabulating mechanism comprising stops settable to arrest the carriage at different positions, computing mechanism, numeral printing keys, a totalizer adjustable to a position corresponding to that of any set stop, said double-spacing means being normally out of the control of the set stops, and means adjustable with the totalizer to control said double-spacing means and cause 30 the same to be operative only by the set stop to which the totalizer is adjusted.

28. In a combined typewriting and computing machine, the combination with a paper carriage and means for propelling

the carriage, escapement mechanism controlling the letter-feed movements of the carriage, computing mechanism, a totalizer arranged to travel with the carriage, tabulating mechanism comprising stops settable to arrest the carriage at different positions, 65 said totalizer adjustable to locate the printing zone at any of said stop positions, mechanism to effect double letter space movement of the carriage at predetermined points during the printing of a number, 70 controlling means for said double-spacing mechanism, said controlling means movable into and out of position to be actuated by the set stops, and means adjustable with the totalizer to hold said means in operative 75 position while the carriage is in the printing zone.

29. In a combined typewriting and computing machine, the combination with a carriage and means for propelling it, of escapement mechanism for effecting letter feed movements of the carriage, tabulating mechanism comprising stops settable to arrest the carriage at predetermined positions, numeral type keys, computing mechanism 90 actuated by said keys, a totalizer connected to travel with the carriage and adjustable to locate the computing zone at any position at which the carriage is arrested by a set tabulator stop, mechanism for effecting double letter space movements of the carriage, a controlling device for said double spacing mechanism movable into and out of an operative position in the path of the set tabulator stops and normally in an 100 inoperative position, and means adjustable with said totalizer and operable automatically to maintain said controlling device in operative relation to the tabulator stops while the totalizer is in the computing zone, 105 whereby said double spacing mechanism is operable to space a numeral being written while the carriage is in the computing zone.

30. In a combined typewriting and computing machine, the combination with a carriage and means for propelling it, of escapement mechanism for effecting letter feed movements of the carriage, tabulating mechanism comprising stops settable to arrest the carriage at predetermined positions, 110 numeral type keys, computing mechanism actuated by said keys, a totalizer connected to travel with the carriage and adjustable to locate the computing zone at any position at which the carriage is arrested by a set tabulator stop, mechanism for effecting double letter space movements of the carriage, a controlling device for said double spacing mechanism movable into and out of an operative position in the path of the 115 set tabulator stops and normally in an inoperative position, means adjustable with said totalizer and operable automatically to 120

125

- maintain said controlling device in operative relation to the tabulator stops while the totalizer is in the computing zone, whereby said double spacing mechanism is operable to space a numeral being written while the carriage is in the computing zone, a key for silencing the computing mechanism, and means actuated by said key for disabling the double spacing mechanism.
- 10 31. In a combined typewriting and computing machine, the combination with a carriage and means for propelling it, of escapement mechanism for effecting letter feed movements of the carriage, tabulating mechanism comprising stops settable to arrest the carriage at predetermined positions, numeral type keys, computing mechanism actuated by said keys, a totalizer connected to travel with the carriage and adjustable to locate the computing zone at any position at which the carriage is arrested by a set tabulator stop, mechanism for effecting double letter space movements of the carriage, a controlling device for said double spacing mechanism movable into and out of an operative position in the path of the set tabulator stops and normally in an inoperative position, means adjustable with said totalizer and operable automatically to maintain said controlling device in operative relation to the tabulator stops while the totalizer is in the computing zone, whereby said double spacing mechanism is operable to space a numeral being written while the carriage is in the computing zone, a case shift key, and means actuated thereby for disabling said double space mechanism.
32. In a combined typewriting and computing machine, the combination with a carriage and means for propelling it, of escapement mechanism for effecting letter feed movements of the carriage, tabulating mechanism comprising stops settable to arrest the carriage at predetermined positions, numeral type keys, computing mechanism actuated by said keys, a totalizer connected to travel with the carriage and adjustable to locate the computing zone at any position at which the carriage is arrested by a set tabulator stop, mechanism for effecting double letter space movements of the carriage, a controlling device for said double spacing mechanism movable into and out of an operative position in the path of the set tabulator stops and normally in an inoperative position, and means adjustable with said totalizer and operable automatically to maintain said controlling device in operative relation to the tabulator stops while the totalizer is in the computing zone, whereby said double spacing mechanism is operable to space a numeral being written while the carriage is in the computing zone, a case shift key, a non-add

key, and means actuated by either the shift 65 key or the non-add key to prevent the double spacing mechanism from operating while the key is in operative position.

33. In a combined typewriting and computing machine, the combination with a carriage, of numeral printing keys, a master wheel, computing mechanism for driving said master wheel and normally out of the control of said keys whereby the keys may be operated without actuating the 70 computing mechanism, means comprising a yielding connection for automatically bringing said computing mechanism within the control of the numeral keys as the carriage enters a computing zone and taking 75 said computing mechanism out of the control of the numeral keys as the carriage passes beyond the computing zone, and means, including a non-computing key, to overcome said connection to take the computing mechanism out of the control of the 80 numeral keys.

34. In a combined typewriting and computing machine, the combination with a carriage, of numeral printing keys, computing mechanism normally out of the control of said keys whereby the keys may be operated without actuating the computing mechanism, means for automatically bringing said computing mechanism within the 95 control of the numeral keys as the carriage enters a computing zone and taking said computing mechanism out of the control of the numeral keys as the carriage passes beyond the computing zone, a case shift key, 100 and means operated thereby to take the computing mechanism out of the control of the numeral keys.

35. In a combined typewriting and computing machine, the combination with a carriage and a platen thereon, of types to print on the platen, keys to actuate said types including numeral keys, a master wheel, mechanism for driving said master wheel, normally ineffective means for transmitting motion from the numeral keys to said driving mechanism, a device, including a yielding connection, for making said transmitting means effective while the carriage is in the computing zone, means, including a key, to overcome said connection and maintain said transmitting means ineffective while the carriage is in a computing zone, and a case-shift actuated device to make said transmitting means ineffective. 110 115 120

36. In a combined typewriting and computing machine, the combination with a carriage and means for propelling it, of letter feed mechanism controlling the letter feed movements of the carriage, mechanism 125 for effecting double letter space movements of the carriage, tabulating mechanism comprising stops settable to arrest the car-

riage at predetermined positions, numeral printing keys, computing mechanism, a totalizer settable at different positions along the carriage to locate the computing zone
 5 at any one of said positions, a tappeted device movable into and out of position to be actuated by the said tabulator stops and normally held out of operative position, said tappeted device operable to actuate
 10 said double spacing mechanism, and means adjustable with the totalizer for maintaining said device in operative position while the carriage is in a computing zone, whereby the double spacing mechanism is controlled only from the stop which positions the carriage at a computing zone.

37. In a combined typewriting and computing machine, the combination with a carriage and means for propelling it, of letter feed mechanism controlling the letter feed movements of the carriage, mechanism for effecting double letter space movements of the carriage, tabulating mechanism comprising stops settable to arrest the carriage at predetermined positions, numeral printing keys, computing mechanism, a totalizer settable at different positions along the carriage to locate the computing zone at any one of said positions, a tappeted device movable into and out of position to be actuated by the said tabulator stops and normally held out of operative position, said tappeted device operable to actuate said double spacing mechanism, and means adjustable with the totalizer for maintaining said device in operative position while the carriage is in a computing zone, whereby the double spacing mechanism is controlled only from the stop which positions the carriage at a computing zone, and means connecting the numeral keys with the computing mechanism to cause the latter to be actuated by the numeral keys while in the computing zone, said keys being automatically disconnected from the computing mechanism while the carriage is outside of the computing zone.

38. In a combined typewriting and computing machine, the combination with computing mechanism and a traveling typewriter carriage for determining computing zones for said computing mechanism, of tabulator stops for said carriage, and means for selectively enabling any one of said tabulator stops to cause a double feed of said carriage in a computing zone.

39. In a combined typewriting and computing machine, the combination with computing mechanism, a traveling typewriter carriage, and tabulator stops carried thereby, of denominational selecting means for said computing mechanism connected to travel with said carriage, mechanism for effecting double letter-space movements of said carriage, a device for controlling said

double-spacing mechanism, movable into and out of operative position in the path of said tabulator stops and normally in inoperative position with respect thereto, yielding connections between said denominational selecting means and said controlling device operable to move said controlling device into operative relation with the tabulator stops whereby said double-spacing mechanism may be operable to space a number being written while the typewriter carriage is in a computing zone, a case-shift key, and means controlled by the said case-shift key for rendering said controlling device ineffective, said means acting on the connections between said denominational selecting means and said controlling device to prevent movement of said connections between the point of yield therein and said controlling device.

40. In a combined typewriting and computing machine, the combination with computing mechanism, a traveling typewriter carriage, and tabulator stops carried thereby, of denominational selecting means for said computing mechanism connected to travel with said carriage, mechanism for effecting double letter-space movements of said carriage, a device for controlling said double-spacing mechanism, movable into and out of operative position in the path of said tabulator stops and normally in inoperative position with respect thereto, yielding connections between said denominational selecting means and said controlling device operable to move said controlling device into operative relation with the tabulator stops whereby said double-spacing mechanism may be operable to space a number being written while the typewriter carriage is in a computing zone, a non-add key, and means controlled by the said non-add key for rendering said controlling device ineffective, said means acting on the connections between said denominational selecting means and said controlling device to prevent movement of said connections between the point of yield therein and said controlling device.

41. In a combined typewriting and computing machine, the combination with computing mechanism, a traveling typewriter carriage, and tabulator stops carried thereby, of denominational selecting means for said computing mechanism connected to travel with said carriage, mechanism for effecting double letter-space movements of said carriage, a device for controlling said double-spacing mechanism, movable into and out of operative position in the path of said tabulator stops and normally in inoperative position with respect thereto, yielding connections between said denominational selecting means and said controlling device operable to move said controlling device into operative relation with the tabulator stops

whereby said double-spacing mechanism may be operable to space a number being written while the typewriter carriage is in a computing zone, a non-add key and a case-shift key, and means controlled by both the non-add key and said case-shift key for rendering said controlling device ineffective, said means acting on the connections between

said denominational selecting means and said controlling device to prevent movement 10 of said connections between the point of yield therein and said controlling device.
